UNITED STATES PATENT OFFICE.

THOMAS H. SYMINGTON, OF ROCHESTER, NEW YORK.

PLATE-SPRING FRICTION.

1,292,536.

Specification of Letters Patent. Patented Jan. 28, 1919.

Application filed March 30, 1915. Serial No. 17,988.

To all whom it may concern:

Be it known that I, THOMAS H. SYMINGTON, a citizen of the United States of America, residing at city of Rochester, county of Monroe, State of New York, have invented certain new and useful Improvements in Plate-Spring Friction, of which the following is a specification.

The subject of this invention is draft rigging of the type in which the shocks in drawing and buffing are absorbed by yielding resilient means inclosed within a box or casing. The invention relates to the construction of the casing, the details thereof, the manner of mounting, supporting and guiding the casing and the draft gear parts, and also to the arrangement of the shock-absorbing members within the casing, the means for guiding, supporting and holding said members, applying the stresses thereto and taking up and preventing wear of the parts.

The use of a heavy, solid cast-iron box for inclosing a series of sets of plate springs for use in railway draft rigging is well-known, but applicant has devised a new and improved type of box which is built up of a number of light sections which can be produced at a comparatively small cost. It is also conveniently assembled and can be taken down instantly to remove and change the springs and spacers when they fail. The spring box is also provided with new and improved means of simple and cheap construction whereby the springs are retained in position and at the same time left freely accessible to the followers for the receipt and transmission of drawing and buffing stresses. In addition to being light, partially flexible and easily taken down, the box which is the subject of this invention is so designed that it is constructed of parts which can be made of pressed steel and conveniently and cheaply rolled and cut from that metal.

Other features of the invention are found in the provision of means on the side of the box for supporting the horizontal yoke and a corresponding flange on the sills for guiding the yoke and holding the parts in position; the use of a double set of springs of half the ordinary width with a central partition in the box to hold them in position; and the use of a plurality of spring boxes, closed at one end and open at the other end, with varying numbers of sets of springs in each box so that if one or more of the springs

in one box fail, the other portions of the gear need not be disassembled to replace the springs.

Another feature of the invention relates to the provision of a hard metal wear plate beneath the springs by means of which the life of the box is considerably increased.

In the accompanying drawings, I have illustrated a draft gear embodying the various features of my invention in the form in which they have first been developed by me.

Figure 1 is a central, vertical, longitudinal section through the draft gear, including the spring box;

Fig. 2 is an enlarged transverse section taken vertically, half on the line A—B and the other half on the line C—D of Fig. 1;

Fig. 3 is a side elevation of the spring box with the springs removed;

Fig. 4 is an end view of the spring box with the springs removed;

Fig. 5 is a longitudinal, vertical, central section of a spring casing consisting of two boxes having their inner ends closed and abutting against each other;

Fig. 6 is an enlarged transverse vertical section, half on the line E—F and half on the line G—G of Fig. 5.

Referring to the drawings by numerals; the structure illustrated includes a draw-bar 1 with a tension member shown in the form of a horizontal yoke 2 inclosing a front follower 3 and a rear follower 4. Between the followers, within the yoke, in Fig. 1, I have shown two series of plate springs 5 within a spring box 10 having a central, vertical, longitudinal partition 16 separating and guiding the two series of springs 5. Each series, in the form of the invention shown in Figs. 1 to 4, is formed of four sets of plate springs the springs of each being placed in contact. The sets of springs are separated by a double convex filler block 9 in the center and two double concave filler blocks 8 between the end and intermediate sets on each side of the center. The followers bear on the centers of the springs outside of the front and rear sets and the drawing and buffing stresses tend to flex the springs and transmit the tension from set to set, and thence, through the followers to the sills in the usual manner.

The spring box 10 is of particular interest in that the top, bottom and sides are separately formed, the top and bottom plates 12 and 13 being flat and preferably

flanged at their lateral edges, the turned edges terminating in ears 14 which are apertured to receive transverse pins 11, four in number one at the top and one at the 5 bottom at each end which hold the plate springs in place and secure the parts of the box in their assembled relation. The sides are also in the form of flat plates 15 apertured at the corners to receive the pins 11 10 and cut away at the front and rear to permit the followers to project within the box and flex the springs, see particularly Figs. 1, 3 and 4.

As has been stated, the spring box is preferably open-ended and formed of these four plates held in assembled position by four transverse pins 11 which in turn engage the ends of the outside springs of the end sets, and hold the springs in position in the box, 15 displacement of the pins 11 being prevented by cotters 17. In addition to these features, the drawings show the sides of the box provided with horizontal flanges 20 which engage the horizontal yoke 2 from beneath and 20 support it. The box itself is supported on the transverse bottom plate 22, bellied down to accommodate the draft gear, and secured at its ends to the opposite sills. The yoke is guided from above and the parts, including 25 the springs, held in position by means of horizontal flanges 21, shown in the form of angle irons secured to the inner faces of the sills 7.

In order to prevent the springs 5 from 30 cutting through the bottom of the box as they work back and forth in being flexed first in one direction and then the other in drawing and buffing, the bottom of the box is protected by means of longitudinal wear 35 plates 18, one on each side of the partition 16, shown as held in position by means of rivets 19.

Referring now to Figs. 5 and 6, I have shown a casing which in assembled form is 40 similar in outline to that shown in Figs. 1 to 4, but in the construction and operation of the two, there are important differences. The casing, in this instance numbered 25, is formed of two separate members 23 and 24, 45 each shown as a box formed in a single piece, closed at one end and open at the other. The sections are of unequal length, the shorter 23 holding a single set of springs or two sets side by side, separated by a central partition, being engaged at the center by the follower 3 on one side and on the other side being engaged at the ends, by a concave filler block 26. The other section 24 contains two sets of springs, one in front of the other, 50 which may be divided longitudinally by a vertical partition 27, so that there are two series side by side, each series being formed of two sets, one in front of the other. Between the front and rear set is a double 55 concave filler block 8. One set of each series

bears centrally against the rear follower 4 and the other set is engaged centrally by a convex filler block 28 which rests on the closed end of the box as does the filler block 26 on the closed adjacent end of the other 70 box. The bottom of each box may be protected by means of a wear plate 18, as shown in the form previously described.

By the use of two boxes thus assembled within the yoke between the followers, it is 75 made possible to so grip the springs that breakage of one spring does not make it necessary to remove the entire set or series of sets in order to replace the broken spring. Aside from this, the separated units are 80 more convenient to handle on account of the weight, and on account of the considerable weight of the springs and casing, this is an important consideration; the other features of the structure may be used with or without 85 the central partitions 27 and 16. Without this partition, full width springs are used.

I have thus described structures embodying my invention in the form in which it has been reduced to practice, in order that 90 the nature and operation of the device may be fully understood; however, the specific terms herein are used in their descriptive, rather than in their limiting sense, and the scope of the invention is defined in the 95 claims.

I claim—

1. In a draft gear, a draw bar, front and rear followers, tension members at the sides secured to the draw bar, a spring box inclosed 100 between the tension members and the followers, springs and spacer blocks within the box, the box being open at the ends and having transverse removable pins at the top and bottom to hold the springs in position. 105

2. In a draft gear, a spring box provided with vertical plate springs and spacer blocks to flex the springs, the box having a bottom wall to support the springs, and a hardened wear plate secured to the bottom of the box 110 and engaging the ends of the springs to prevent wear of the box.

3. In a draft gear, a spring box open at the ends, co-operating followers moving relatively to the box at the ends, the box having 115 a central longitudinal partition and two series of spring plates and spacer blocks, one on each side of the partition.

4. In a draft gear, a draw bar, a tension member secured to the draw bar and having 120 an opening, a spring casing within the opening composed of two sections each in the form of a box open at one end and closed at the other, the closed ends being juxtaposed, followers at the front and rear openings, one box having a set of springs engaging the follower and a spacer block engaging the other side of the same set and in contact with the closed end of the box, the other box having a set of springs engaging the 125 130

follower at that end, a double concave filler block in contact with the opposite side of the same set of springs, a second set of springs between the concave filler block and the 5 closed end of the box, and a convex filler block engaging the closed end of the box and bearing against the opposite side of the latter set of springs.

5. In a draft gear, a draw bar, front and 10 rear followers, tension members at the sides of the draw bar and followers, a spring box inclosed between the tension members and followers, the box being formed of four metal sheets having apertures in alinement and 15 transverse pins passing through the apertures to hold the box in assembled position,

springs and spacer blocks within the box held in position by the transverse pins.

6. In a draft gear, a draw bar, front and rear followers, tension members at the sides 20 of the draw bar and followers, a spring box inclosed between the tension members and followers, the box being formed of four metal sheets having apertures in alinement and means passing through the apertures to 25 hold the spring box in assembled position.

Signed by me at Baltimore, Maryland,
this 8th day of March, 1915.

THOMAS H. SYMINGTON.
